UNITED STATES PATENT OFFICE.

DANIEL S. DUNHAM, OF SAN ANTONIO, TEXAS.

DESIGN FOR A LAPEL-BUTTON, FOB, RING, OR SIMILAR ARTICLE OF JEWELRY.

53,895.

Specification for Design.

Patented Oct. 7, 1919.

Application filed February 6, 1919. Serial No. 275,476. Term of patent 7 years.

To all whom it may concern:

Be it known that I, DANIEL S. DUNHAM, a citizen of the United States, residing at San Antonio, in the county of Bexar and State of Texas, have invented a new, original and ornamental Design for Lapel-Buttons, Fobs, Rings, or Similar Articles of Jewelry, of which the following is the specification, reference being had to the accompanying drawing, forming a part thereof.

The figure is a plan view of my new design.

I claim:

The ornamental design for a lapel button, fob, ring, or similar article of jewelry, as shown.

DANIEL S. DUNHAM.

Witnesses:

VEVA HANNSZ,
ED F. BURKE.
